UNITED STATES PATENT OFFICE.

JAMES H. REINHARDT, OF MEMPHIS, TENNESSEE, ASSIGNOR, BY DIRECT AND MESNE ASSIGNMENTS, TO THE REINHARDT NUMBERING MACHINE COMPANY.

CONSECUTIVE-NUMBERING MACHINE.

SPECIFICATION forming part of Letters Patent No. 353,711, dated December 7, 1886.

Application filed August 24, 1885. Serial No. 175,171. (No model.)

To all whom it may concern:

Be it known that I, JAMES H. REINHARDT, of Memphis, in the county of Shelby and State of Tennessee, have invented a new and useful 5 Improvement in Consecutive-Numbering Machines; and I do hereby declare that the following is a full and exact description thereof, reference being had to the accompanying drawings, and to the letters of reference marked 10 thereon, making a part of this specification.

Figure 1 is a plan view of one of my improved machines constructed for numbering consecutively ten tickets at one impression; Fig. 2, a view in perspective of the swinging 15 pawl-frame by which the numbering-wheels are actuated, showing, however, only a portion of its pawls, and illustrating one of the fixed numbering-plates of the device in position; Fig. 3, a transverse section in line $x-x$ of Fig. 20 1, illustrating the slot and pin by which the frame is actuated; Fig. 4, a transverse section in line $y-y$ of Fig. 1, illustrating the action of the pawls carried by the swinging frame; Fig. 5, a longitudinal section through one section 25 of the machine with its numbering-wheels removed, illustrating the combination of the actuating-plunger with the swinging frame; Fig. 6, an elevation of one of the fixed numbering-plates detached; and Fig. 7 a transverse section in line $z-z$ of Fig. 6, but showing a different attachment of the type to the plate; Fig. 30 8, a horizontal section in line $w-w$ of Fig. 3, illustrating the device by which the movement of the plunger is made to oscillate the 35 swinging pawl-frame.

My invention relates to an improvement in that class of consecutive-numbering machines for which Letters Patent of the United States were granted to Reinhardt and Ellis, bearing 40 date May 26, 1885, No. 318,803, and has for its object to facilitate the printing of successive sets of consecutively-numbered cards, checks, or tickets at one impression, the numbers being changed automatically after each impression, so that each set printed shall bear consecutive numbers, following in regular order the numbers of the preceding set, whereby, for 45 example, a sheet of one hundred cards may be

printed at one impression, and consecutively numbered at the same impression with figures 50 from 1 to 100, and at the next movement of the press for printing the second sheet the cards thereon will be consecutively numbered from 101 to 200, the next sheet from 201 to 300, and so on, the change in the numbering-wheels being produced automatically after each impression. 55

As my invention is designed especially for the rapid printing of large quantities of consecutively-numbered checks or tickets, it will 60 doubtless be found expedient to construct machines each having ten sets of wheels to facilitate the arrangement of ten of them in a press for printing as one impression one hundred separate checks or tickets, and I have illustrated this form of construction in Fig. 1.

My invention is applicable, however, to small machines including one set of wheels only, the desired result of printing simultaneously a considerable number of the separate checks or 65 tickets by a single impression being obtained by placing in proper order in a single form any desired number of these single machines. 70

Each machine is in its general features constructed substantially as is described in my 75 aforesaid Letters Patent of May 26, 1885—viz., of a series of two, three, or more type-wheels, A A A, revolving side by side upon an axial shaft, B, the face of each wheel on one side being fitted with a ratchet, c, (see Fig. 4,) and 80 its opposite face with a circular flange or offset, d, whose diameter corresponds to the extreme diameter of the ratchet-wheel, so that when the wheels are placed side by side with the flange on one in proximity to the ratchet 85 of the other, a pawl, W, dropped between them, shall ride upon the flange until permitted by a notch cut therein to fall into engagement with the adjoining ratchet. The pawls W W, which thus severally actuate the ratchets on 90 one wheel, when permitted by a notch in the flange of the next, are secured to a single longitudinal rod, E', (see Figs. 2 and 4,) in a swinging frame, E' E' E', pivoted upon the shaft B, and vibrating under the wheels A A. This 95 swinging frame is made to vibrate by means of

a spring-seated plunger, G, mounted at one end of the series of wheels in a suitable case, H. (See Fig. 5.) A transverse or radial slot, q, is cut in the end piece, E', of the frame (see Fig. 2, and dotted lines, Fig. 3) in register with a curved slot, r, in the fixed partition T, which separates this end plate, E', of the swinging frame from the plunger G. A lever, m, is pivoted to the inner side of the partition T, next to the plunger, to extend horizontally across the slot r therein, and its opposite face is also pivoted at a short distance from its fulcrum-point or pivot to the plunger, as shown in Fig. 8. A pin, f, is made to project from the free end of this lever m through the two slots q and r. As the end of the lever between the pin f and the pivotal connection of the lever to the plunger is longer than the portion between said pin and the pivotal fulcrum of the lever, a comparatively slight movement of the plunger will operate to produce an extended movement of the pin f, and consequently of the swinging plate E' and frame E E'. A reverse movement of the several wheels is prevented by stationary pawls or detents s s, pivoted to the case on the opposite side of the pawls W W, as shown in Fig. 4. By pressing down the plunger G the swinging frame E E' is carried forward, so that its pawls W W shall ride over the ratchets far enough to turn, upon the return movement of the frame, the wheels whose ratchets they may engage the distance required to make a single change of the type thereon in reference to the line of print, this return movement being produced by the upward stroke of the plunger.

In my present invention I fix at the left hand of each series of wheels, whether it be a single series (see Fig. 5) or a number of series mounted together in a single extended case, (see Fig. 1,) a transverse plate, K, upon whose upper surface are formed or fitted one or more types indicating the unit or right-hand figure or figures of the numbers to be printed on the checks. Where several series of numbering-wheels are combined in one machine these stationary figures are made to represent consecutive numbers in order from left to right upon the several transverse plates, K K—as, for example, 10, 20, 30, 40, &c., (see Fig. 1)—and where a number of separate single machines are employed for the simultaneous printing of a number of checks, the left-hand plate in each is provided with a different digital number, so that in use the machine may be arranged as required to present a series of different fixed consecutive numbers from left to right, one of the fixed numbers being on the left of each series of numbering-wheels. The type upon these fixed transverse plates K may be either cast in one with the plate or be made detachable therefrom, either by means of a plate, i, made to slide into a transverse dovetailed slot in the top of the plate K, (see Figs. 2 and 6,) or as loose type t, to be inserted and locked in a recess or socket formed to receive them in the top of the plate, (see

Fig. 7,) or in such other manner as will suggest itself to a skilled artisan.

Where several series of numbering-wheels are combined in one machine, as illustrated in Fig. 1, the bottom edge of the fixed numbering-plate K is recessed, (seen at n, Fig. 6,) to permit the longitudinal lower bar, E, of the frame to extend and vibrate freely under the plate. (See Fig. 2.) The long swinging frame E E E' is stiffened by means of transverse plates L L, (see Fig. 2,) which are adapted to fit one within each compartment of the machine.

The fixed numbering-plates K K, against which the swinging transverse plate plays, are recessed each on its lateral face to receive the thickness of the adjacent plate L, (see Figs. 6 and 7, and dotted lines Fig. 1,) and thereby permit the spacing between the type on the fixed plate K and those on the numbering-wheels A A to be uniform. The swinging frame E E' is made to oscillate by the plungers G G, mounted at each end of the case, which operate in unison when the platen of the press strikes them as it drops to produce an impression from the form of type in the press.

In the use of my machine, if it be desired to print simultaneously at each movement of the press one hundred consecutively-numbered cards, the cards printed at each impression to follow in regular order of numeration those printed at the preceding impression, one hundred single machines, which bear severally each upon its fixed numbering-plate two figures embracing all the numbers running from 1 to 100, are arranged in order, a cipher being placed at the left of each single digit, so that the numbers in the fixed plates shall be consecutive; or, preferably, ten ten-section machines (see Fig. 1) are arranged, the first bearing numbers on its fixed plates from 1 to 10, the second from 11 to 20, the third from 21 to 30, and so on, so that the numbers on all of the one hundred fixed plates shall fall in consecutive order, the last fixed plate bearing simply 00. The numbering-wheels are then all turned to 0, excepting the last in the entire series, which is turned to 1. At the first impression the numbers on the fixed plates K K will be printed severally on the one hundred cards, with ciphers to the left of them, so that the first card shall be numbered 000001, and the last 000100. Upon the release of the plungers G G from the pressure of the plates, they will operate as they are thrown up by the action of their springs to oscillate the swinging frame E E', and thereby move the first wheel in each series from 0 to 1, excepting the wheel in the last, which being already at 1 moves to 2, and at the next impression the cards will each be printed with the figure 1, from the first wheel to the left of the numbers on each fixed plate, excepting the last, which will be printed with the figure 2; hence the first card will at the second impression be printed with 01 from the fixed plate, and with 1 to the left from the numbering-

wheel, making 101. The second card will be printed with 102, the tenth with 110, and the one hundredth with 200.

I claim as my invention—

- 5 1. The combination, in a consecutive-numbering machine, with two or more sets of numbering-wheels rotating upon a common axial shaft, of a fixed partition-plate at the right of each set of wheels, each bearing upon its upper 10 surface one or more stationary type in line of print, to produce, in connection with the type upon the wheels to the left, the first or left-hand figures in a number completed by the movable type on the wheels, substantially in 15 the manner and for the purpose herein set forth.
2. The combination, in a consecutive-numbering machine, with its swinging-pawl frame, mechanism, substantially as described, for oscillating said frame, pawls carried by the frame, and two or more sets of numbering-wheels rotating upon a common axial shaft and actuated by said pawls, of partition-plates fixed at the right of each set of wheels, each bearing upon its 25 upper surface one or more stationary types in
- line of print with the uppermost type on the wheel, and each perforated to allow the shaft to extend through it, and recessed upon its lower side to permit of the play of the swinging frame under it, substantially in the manner 30 and for the purpose herein set forth.
3. The combination, in a consecutive-numbering machine, with its swinging-pawl frame, its plunger, and with registering intersecting slots in the end plate of the swinging frame, 35 and in the adjacent fixed partition-plate separating it from the plunger, of a lever pivoted at one end to said partition-plate and at the other to the plunger, and an intermediate pin projecting from the lever through the two 40 slots, substantially in the manner and for the purpose herein set forth.

In testimony whereof I have signed my name to this specification in the presence of two subscribing witnesses.

JAMES H. REINHARDT.
